COOLING BED

George W. Rauschenberger, Ecorse, Mich., assignor to National Steel Corporation, a corporation of Delaware

Application November 8, 1943, Serial No. 509,368

6 Claims.

(Cl. 80—42)

The present invention relates to a cooling bed for cooling rounds, rods, bars, shapes, or the like, after they have been rolled on a mill, such as the type commonly called a "merchant" mill. More particularly, it relates to a cooling bed provided with a plurality of stops or spacing members which operate to maintain the rounds in proper position on the bed and cause them to move forwardly along the bed and be delivered to the discharge end of the bed and to the shearing mechanism located adjacent the end of the bed at a proper shearing temperature.

Heretofore considerable difficulty has been encountered in the operation of merchant mills in delivering rounds from the cooling bed to the shearing mechanism at the proper shearing temperature. Merchant mills are generally employed for the rolling of rounds, bars, rods and various shapes. When the rolling of the material on the mill is completed, the rounds, bars, etc., are red hot and must be cooled to some extent before shearing and further handling. Consequently, they are delivered by the mill to one end of a cooling bed over which they travel. The cooling bed is of such dimensions and is operated at such speed that the material during its travel thereover cools slowly to a predetermined temperature, which is sufficiently low to permit some annealing thereof, and to deliver it to the shearing mechanism at the proper temperature for shearing. Such cooling beds are generally of the walking-beam type in which alternate beams are reciprocated vertically and horizontally or horizontally only and intermediate beams are reciprocated vertically only or both horizontally and vertically.

In the conventional cooling bed, flat-topped beams are generally employed for transporting the material throughout a portion of the travel of the material. When bars or other rectangular or similar shapes are rolled, no difficulty is encountered as such products will remain in deposited position on the flat-topped surface portions of the beams, and there is no tendency for them to move rearwardly therealong. However, where rounds or rods are being rolled and passed over the flat section of the cooling bed, they roll around and are not carried forwardly until they are actually pushed by succeeding bars coming from the mill. The result is that rounds remain on the cooling bed for too long a period of time and cool to too great an extent for subsequent shearing. Moreover, the rounds are not on the cooling bed for a uniform period of time and, consequently, some of them are cooled to a greater extent than others. This renders them non-uniform

from the standpoint of the annealing of the product and also creates difficulty in the shearing thereof.

A portion of the conventional cooling bed is formed of beams having a notched top surface which will cause the bars, rounds, rods or shapes to move over this portion of the bed at the proper rate of speed, but it has been found desirable where various shapes are being rolled on the mill to have a portion of the cooling bed, and particularly the portion closest the discharge end, formed of beams having a flat top surface.

The difficulties mentioned above in respect of the rolling of rounds, rods and the like are overcome by the present invention by the provision of means which is mounted for reciprocation with at least some of the beams and which is movable from an inoperative position to an operative position above the top surfaces of the beams for preventing the rounds from moving rearwardly along the beams and for causing them to move forwardly at the desired rate of speed, whereby they are delivered to the discharge end of the cooling bed and to the shearing mechanism at the proper temperature. The means for causing the rounds to move at the proper rate over the cooling bed may be carried by the walking beams themselves or they may be carried on any other portion of the bed which is reciprocated with the beams. It is only necessary that they be movable from an inoperative position in which they will not interfere with the movement of square or rectangular shapes over the bed to an operative position where they will prevent the rounds or rods from moving rearwardly and cause them to move forwardly at the desired speed. Consequently, my invention is not limited to the use of stop members which are carried directly by the beams. Nor is my invention limited to any specific type stop member capable of being moved from an inoperative position to an operative position as the stop members may assume various different forms.

In the accompanying drawings I have shown for purposes of illustration only a preferred embodiment of my invention. In the drawings my invention is illustrated as applied to the ordinary walking beam type of structure. It will be understood, however, that my invention may be embodied in various different types of apparatus and may be applied to cooling beds other than those of the walking-beam type.

In the drawings, Figure 1 is a side elevation of a cooling bed embodying my invention;

Figure 2 is an enlarged side elevational view of a portion of the cooling bed shown in Figure 1;

Figure 3 is a partial plan view of the portion of the cooling bed illustrated in Figure 2;

Figure 4 is an enlarged partial side elevational view of a portion of the beam shown in Figure 2;

Figure 5 is a section taken along line V—V of Figure 4;

Figure 6 is a plan view of one of the movable stop members shown attached to some of the beams illustrated in Figures 1 to 4, inclusive;

Figure 7 is a side elevational view of the movable stop member shown in Figure 6.

In the embodiment illustrated in the drawings the rounds are fed to the approach table 2 from the mill in a direction normal to the direction in which they travel along the bed. They travel along the bed from left to right, as shown in Figure 1. The rounds are fed from the approach table to the cooling bed by means of a pusher mechanism 3 spaced along the approach table between the rollers thereof.

The rounds are fed from the approach table to the portion 4 of the cooling bed which is made up of a plurality of spaced notch or rack bars 5. Alternate notch bars are supported on transversely extending beams 6 and 7; that is, one bar is mounted on beams 6 and the next adjacent bars are mounted on beams 7. These beams are supported for reciprocation so as to provide a walking beam movement for the notch bars.

Various types of walking beam movements are well known in the art to which this invention relates. In one type, alternate bars are reciprocated horizontally and vertically and the intermediate ones are reciprocated vertically only. In another well-known type, all the bars are reciprocated both vertically and horizontally, adjacent bars moving in opposite directions. In the type of structure shown in the drawings, alternate bars 5 are mounted for both vertical and horizontal reciprocation and the intermediate bars are mounted for only vertical reciprocation. Horizontal reciprocation of alternate bars 5 is effected by shafts 8, rockers 9 and connecting rods 10 and 11. Vertical reciprocation of the bars is effected by driving mechanism 12 connected to the various beams through pipes 13. In view of the fact that the present invention is not addressed to or particularly concerned with the reciprocatory mechanism, a detailed discussion thereof is unnecessary. It will suffice to state that as alternate notch bars move forwardly while supporting the rounds, the intermediate bars are not in contact with the rounds. When the notch bars have reached the forward end of their travel, the intermediate bars are raised to receive the rounds. The alternate notch bars are then lowered and moved rearwardly. When they have reached the end of their rearward travel they are moved upwardly to receive the rounds and the intermediate ones are lowered. After the rounds have been transferred from one set of notch bars to the other, the one set moves forwardly again. Thus the rounds are caused to move forwardly over the bed.

After the rounds have traversed the rack bars they are transferred to the flat-topped beams 14. The ends of these beams adjacent the rack bars extend between the ends of the rack bars so that the rounds can be transferred directly thereto. This portion of the cooling bed comprises a plurality of spaced beams 14, some of which are carried on transverse beams 15 and some on transverse beams 16. These beams are

arranged to be vertically reciprocated by pipes 17 and driving mechanism 18. Alternate beams are also arranged to be driven by reciprocating mechanism for moving them horizontally. The same type of walking-beam movement, therefore, is provided for the beams 14 as that for the notch bars 5.

After the rounds have traversed the beams 14 they are discharged therefrom onto a table 19. They are then transferred to a shear approach table 20 or a shear approach table 21. The approach table then carries the rounds to the shearing mechanism where they are sheared to the proper size.

As stated above, difficulties have been encountered heretofore in the handling of rounds during their passage along that portion of the table comprising the flat-topped beams 14. When the rounds are supported by the vertically movable flat-topped beams there is a tendency for them to roll around to some extent and not maintain their proper position. When the rounds are picked up for forward movement by the vertically and horizontally reciprocable beams they are not maintained in proper position and instead of moving forwardly with the beams they roll rearwardly therewith and are not carried forward until they are pushed forward by succeeding bars being discharged from the notch bar section of the cooling bed. As a consequence, this leaves the rounds on the flat-topped section of the bed for too long a period of time and they become too cold for shearing.

In accordance with my invention, I provide means movable from an inoperative position slightly below the top surfaces of some of the beams to an operative position above the top surfaces thereof for holding the rounds in position on the beams or for causing them to move forwardly with the horizontally reciprocable beams at the proper predetermined speed. I provide a plurality of spaced stop members 22 cooperating with any desired number of beams. It is unnecessary to provide spaced stop members cooperating with all of the beams. It is necessary only that two of the beams carrying the rounds at any particular time have cooperating stop members to prevent the rounds from moving out of position thereon. As shown in Figure 3, these stop members may be placed on two adjacent beams at several points along the width of the cooling bed. They are provided on adjacent beams because one of the beams carrying the stop members is reciprocated vertically and horizontally and the other is reciprocated vertically only. While stop members are not absolutely necessary on the beams which do not carry the rounds forwardly, it is desirable to place them on these beams as well as upon those which do move the rounds forwardly in order to prevent them from rolling rearwardly during the rearward stroke of the horizontally reciprocating beams.

The stop members shown in the drawings are in the form of hinges carried by the beams. Each hinge comprises an angular supporting portion 23, a movable portion 24, and a pivot pin 26 about which the movable portion rotates. A plate 25 is attached to the movable portion 24 of the hinge but this plate is not necessary where specially designed stop members, instead of ordinary hinges, are employed. The angular supporting portion 23 is welded to the web and the bottom of the top flange of the supporting beam. The 75 pivot pin 26 is positioned below the top surface

of the beam so that it will not interfere in any way with the movement of work along the cooling bed when rectangular bars or shapes are being carried thereby. The movable portion 24 of each stop member is bent so that it will extend horizontally along the top surface of the beam when rotated to this position. When the cooling bed is carrying rounds the stop members are moved into position on the tops of the beams, and when the bed is carrying rectangular or other shapes these stop members need not be used and may be moved to a position below the top surface of the beam so that they will not interfere with the material passing therealong.

The simplicity of my invention is well illustrated by the fact that ordinary hinges may be employed if desired. All that is necessary is to bend them to the proper shape and to weld them to the beams. A plate, such as the plate 25, can be welded to the movable portion of the hinge 20 so as to provide a thicker stop member than would be present if the hinge were used in its usual condition.

In the drawings I have shown the stop members carried by the reciprocating beams. It will be apparent that these stop members need not be carried by the beams but may be carried on other reciprocating parts of the bed. For example, they may be carried on the walkways which are generally positioned between some of the beams in the ordinary type of cooling bed. It is only necessary that these stop members be reciprocable with the beams and movable into and out of an operative position above the top surfaces of the beams.

While I have shown and described a preferred embodiment of my invention, it will be understood that it may be otherwise embodied within the scope of the appended claims.

I claim:

1. A cooling bed for rounds, bars or the like comprising a plurality of spaced beams adapted to support the rounds, means for horizontally reciprocating at least some of the beams to move the rounds forwardly along the cooling bed, and stop members mounted for reciprocation with at least some of the beams, each of said stop members comprising a pivotally mounted arm movable from an inoperative position below the top surfaces of said beams to an operative position on the top thereof for holding the rounds in position on the beams to cause them to move with the beams.

2. A cooling bed for rounds, bars or the like comprising a plurality of spaced beams adapted

5 to support the rounds, means for vertically and horizontally reciprocating at least some of the beams to move the rounds forwardly along the cooling bed, and means carried by at least some of the beams and movable from an inoperative position below the top surfaces of said beams to an operative position above the top surfaces thereof for holding the rounds in position on the beams and for causing them to move forwardly with said beams during forward movement thereof.

10 3. A cooling bed for rounds, bars or the like comprising a plurality of spaced beams adapted to support the rounds, means for vertically and horizontally reciprocating alternate beams, means for vertically reciprocating intermediate beams, and stop members mounted for reciprocation with at least some of said beams and movable from an inoperative position below the top surfaces of said beams to an operative position above the top surfaces thereof for maintaining the rounds in position on the beams.

15 4. A cooling bed for rounds, bars or the like comprising a plurality of spaced beams adapted to support the rounds, means for horizontally reciprocating alternate beams, means for vertically reciprocating intermediate beams, stop members mounted for reciprocation with some of said alternate beams and with some of said intermediate beams and movable from an inoperative position below the top surfaces of said beams to an operative position above the top surfaces thereof for properly positioning the rounds and for carrying them forwardly over the cooling bed.

20 5. A cooling bed for rounds, bars or the like comprising a plurality of spaced beams adapted to support the rounds, means for moving the rounds along the beams, and stop members carried by at least some of said beams, each stop member comprising a pivotally mounted arm movable from a position below the top surface of the beam on which it is mounted to a position on the top thereof.

25 6. A cooling bed for rounds, bars or the like comprising a plurality of spaced supporting means adapted to support the rounds, a plurality of beams for moving the rounds along the supporting members, means for reciprocating said beams horizontally, and stop members carried by at least some of said beams, each stop member comprising a pivotally mounted arm movable from a position below the top surface of the beam on which it is mounted to a position on the top thereof.

55 GEORGE W. RAUSCHENBERGER.
